(57) **CLAIM**

The ornamental design for a bedbug trap, as shown and described.

DESCRIPTION

FIG. 1 is a perspective top front right view of a bedbug trap, showing our new design;

FIG. 2 is a front elevation view thereof, wherein the rear elevation view is an identical image thereof;

FIG. 3 is a left elevation view thereof, wherein the right elevation view is an identical image thereof;

FIG. 4 is a top plan view thereof; and,

FIG. 5 is a bottom plan view thereof.
